Primary Examiner — Darlington Ly

(57) **CLAIM**

The ornamental design for a cordless planer, as shown and described.

DESCRIPTION

1.1 is a front elevation view embodying our cordless planer;

1.2 is a rear elevation view thereof;

1.3 is a left elevation view thereof;

1.4 is a right elevation view thereof;

1.5 is a top plan view thereof;

1.6 is a bottom plan view thereof; and

1.7 is a perspective view thereof.

The broken lines are for the purposes of illustrating portions of the cordless planer and form no part of the claimed design.

1 Claim, 7 Drawing Sheets
